UNITED STATES PATENT OFFICE.

HOWARD E. WATKINS, OF NEW YORK, N. Y., ASSIGNOR TO THE OXLEY & ENOS MANUFACTURING COMPANY, OF SAME PLACE.

DESIGN FOR AN ORNAMENTAL TUBE FOR GAS OR ELECTRIC FIXTURES.

SPECIFICATION forming part of Design No. 33,461, dated October 30, 1900.

Application filed August 21, 1900. Serial No. 27,629. Term of patent 7 years.

To all whom it may concern:

Be it known that I, HOWARD E. WATKINS, a citizen of the United States of America, residing at 371 Fifth avenue, in the borough of

5 Manhattan, city of New York, county of New York, and State of New York, have invented and produced a new and useful Design for Ornamental Tubes for Use on Gas and Electric Fixtures and Similar Articles, of which

10 the following is a full and complete specification, reference being had to the accompanying drawings, forming a part thereof.

Figure 1 represents a side view, and Fig. 2 a cross-section, of a tube, showing my design.

15 The design consists of a flaring tube, the lower part of which is marked longitudinally to suggest in a conventional manner the stems of the flowers and leaves facing the upper part of the tube, and the upper part of

20 which is curved outward and downward, said

upper curved surface being marked to represent alternately bunches of small flowers of conventional type and broad oblanceolate leaves.

In the annexed drawings, A represents the 25 lower part of the tube; B B, the markings suggesting the stems; C, the curved upper part of the tube; D D, the bunches of flowers, and E E the broad leaves.

The essential features of the design are 30 those above indicated.

Having described my invention, what I claim as new, and desire to secure by Letters Patent, is—

The design for an ornamental tube for fixtures, as herein shown and described.

HOWARD E. WATKINS.
